UNITED STATES PATENT OFFICE.

HERMANN HAAS, OF LENNEP, GERMANY.

DRYING APPARATUS.

Application filed December 2, 1925, Serial No. 72,715, and in Germany December 4, 1924.

This invention relates to drying apparatus of that type which comprises a plurality of drying chambers and a plurality of heating chambers arranged alternately so that a drying current may be passed through the chambers successively. In prior drying apparatus of this type it has been the common practice to employ a single air-forcing mechanism usually in the form of an ex-
hauster or suction apparatus which operates to draw the drying current through the series of chambers, the drying current being drawn into a heating chamber where it is heated and then passing to the adjacent drying chamber where it performs its drying function and then passing into the next heating chamber where it is reheated from which it passes to another drying chamber and so on.
This arrangement has the disadvantage that since the single suction apparatus or exhauster is required to draw the air current through all the chambers successively it is necessary to operate the exhauster with a considerable vacuum in order to overcome the resistance which the air meets in passing through all the drying and heating chambers successively, this being the combined resistance in all the chambers.
As is well known the power consumption of a centrifugal blower or other suction apparatus is determined by the quantity of air which is moved and the degree of vacuum which is created. The higher the vacuum the greater will be the power consumption.

My invention has for its object to improve a drying apparatus of the above type which has alternately arranged heating and drying chambers by providing a construction by which the required movement of air will be secured through the chambers to effect the necessary drying with a considerably reduced power consumption.

In order to give an understanding of the invention I have illustrated in the drawings a selected embodiment thereof which will now be described after which the novel features will be pointed out in the appended claims.

Fig. 1 of the drawings is a sectional view illustrating an apparatus of the type which has heretofore been used;

Fig. 2 is a similar view illustrating an apparatus embodying my invention;

Fig. 3 is a section on the line 3—3, Fig. 2; Referring first to Fig. 1, 1, 2, and 3 in-

dicate drying chambers and 4, 5, and 6 indicate heating chambers, said heating chambers having some suitable heating means therein such for instance as a steam pipe 7. 60 These heating and drying chambers are arranged in alternation and communicate with each other so that there is a heating chamber between each two adjacent drying chambers and conversely a drying chamber be- 65 tween two adjacent heating chambers.

The heating chamber 4 has an opening 8 at its upper end through which a drying air current may be admitted and at its lower end it communicates with the drying chamber 1 through an opening 9. The drying chamber 1 communicates with the upper end of the heating chamber 5 through an opening 10 and said heating chamber 5 communicates at its lower end with the drying chamber 2 through an opening 11. The drying chamber 2 also has communication with the heating chamber 6 through an opening 12 and said heating chamber 6 communicates at its lower end with the drying chamber 3 through the opening 13.

14 indicates a suction or exhaust apparatus, the inlet of which has communication with a pipe 15, the latter having ports or openings 16 leading to the various drying chambers. Each opening is provided with a closure 17 by which it may be closed as shown in Fig. 1. The closure 17 for the opening 16 leading to the last drying chamber 3 is open, the other closures being closed and with this arrangement the exhauster 4 will draw air in through the opening 8 and pass it successively through the heating and drying chambers as indicated by the line of arrows 18. With this arrangement the suction apparatus has to develop sufficient suction or vacuum to overcome the combined resistance in all of the chambers. 90

The improvements constituting the present invention consist of employing a plurality of blowers, one for each drying chamber, each blower being arranged to cause a local circulation through each drying chamber and the corresponding heating chamber and also to cause a progressive movement of the air through the drying chambers and heating chambers. 100

In Fig. 2, which illustrates my improvement, 19, 20 and 21 indicate drying chambers and 22, 23 and 24 indicate the corresponding heating chambers, each heating chamber having the heating pipes 25 there-

in. Each heating chamber communicates with its corresponding drying chamber at both the top and the bottom and also communicates with the next adjacent drying chamber. For instance, the heating chamber 24 communicates with its drying chamber 21 through the top opening 32 and the bottom opening 31 and communicates with the adjacent drying chamber 20 through the opening 33. The heating chamber 23 communicates with its drying chamber 20 through the top opening 29 and the bottom opening 28 and also communicates with the adjacent drying chamber 19 through the opening 30. The heating chamber 22 communicates with its drying chamber 19 through the top opening 27 and bottom opening 26 and also communicates with the drying chamber 21 through a passage or conduit 44 one end of said passage communicating with the upper end of the heating chamber 22 and the other end of the passage communicating with the chamber 21 through the opening 49.

Each drying chamber has an inlet opening 39 leading thereto and a closure 40 for this opening. These closures may be independently opened so that the different inlet openings 39 may be selectively opened or closed. Each drying chamber also has an outlet or discharge opening 41 leading to a conduit 42 which communicates with the atmosphere and each discharge opening 41 has a closure 43 by which it may be opened or closed. The closures 43 are capable of independent operation and thus the heating chambers may be selectively connected to the atmosphere.

Each drying chamber has associated therewith a blower or air-forcing device, these blowers being indicated at 34, 35, 36. The blowers are located at the upper openings between the drying chambers and heating chambers and preferably all are mounted on the same shaft 37 which may be driven in any suitable way as by means of a driving pulley 38.

In the operation of the device the exhaust opening 41 of the heating chamber which corresponds to the drying chamber having the wettest material therein will be opened, the exhaust openings 41 of the other drying chambers being closed, and the inlet opening 39 of the drying chamber having the dryest material therein will be opened, the other inlet openings being closed. As shown in Fig. 2 it is assumed that the drying chamber 19 has the wettest material therein and the drying chamber 21 the dryest.

When the shaft 37 is rotated and the windwheels or air-forcing devices 34, 35 and 36 are operated each windwheel will set up a local current through its heating chamber and drying chamber as shown by the dotted lines Fig. 2, each local current pass-

ing downwardly through the heating chamber and then into the lower end of the corresponding drying chamber and thence back into the heating chamber again where it passes downwardly. In addition to these local currents there will be a gradual or progressive movement of the air through the chambers successively as indicated by the full lines, the air entering continuously through the open inlet port 39 (this port being the inlet port leading to the chamber having the dryest material therein) and passing progressively through the drying and heating chambers successively to the open discharge port 41 (which will be the discharge port of the chamber having the wettest material therein). Hence with this arrangement there will be a local circulation through each heating chamber and its drying chamber and a progressive movement of the air from the chamber having the dryest material to the chamber having the wettest material therein.

When the material in the chamber 21 is thoroughly dried it may be removed and the chamber filled with wet material which is to be dried. When this is done the chamber 20 will then have the dryest material therein and the chamber 21 the wettest material and to continue the drying operation the inlet portion 39 leading to the chamber 21 will be closed while the inlet port leading to the chamber 20 will be opened. Similarly, the discharge port 41 leading from the heating chamber 22 will be closed and that leading from the heating chamber 24 will be opened. When this is done then the air will be entering continuously through the inlet port into the chamber 20 which now contains the dryest material and will pass progressively through the heating chamber 23 through the drying chamber 19 and through the conduit 44 into the drying chamber 21 which contains the wettest material from which it will be discharged.

When the material in the chamber 20 becomes thoroughly dried it may be removed and the chamber filled with wet material at which time the chamber 19 will contain the dryest material and the chamber 20 the wettest material. The inlet valve 39 leading to the chamber 20 is then closed and that leading to the chamber 19 is opened while the discharge opening 41 leading from the chamber 21 is closed and that leading from the chamber 20 is opened. Upon continued operation there will be not only the local circulation set up as heretofore described but a continuous progressive circulation through the chambers beginning with the chamber 19 having the dryest material therein and ending with the chamber 20 having the wettest material therein. The chambers may thus be emptied and filled progressively as the drying proceeds and at

all times there will be both a local circulation indicated by the dotted lines and the progressive circulation through the series of chambers, which progressive circulation always starts with the chamber having the dryest material therein, and ends with the chamber having the wettest material therein.

Another advantage gained from this structure is that each windwheel has to overcome only the resistance of its local circulation and, therefore, it will not be necessary for the windwheels to operate under such high vacuum as would be the case in the construction shown in Fig. 1. The apparatus shown in Fig. 2, therefore, can be operated with a much less consumption of power than one such as shown in Fig. 1. Practical tests in dryers have shown that of two dryers of the same size, one constructed as shown in Fig. 1 and the other as shown in Fig. 2, a dryer as illustrated in Fig. 2 will require only about one-half the power that is required to operate the dryer constructed in Fig. 1.

I claim:

1. A drying apparatus comprising a plurality of drying chambers, a heating chamber for each drying chamber, each heating chamber communicating with its drying chamber at both the top and the bottom

and also communicating with an adjacent drying chamber, a blower for each drying chamber by which a local circulation is established through said drying chamber and corresponding heating chamber, each of the drying chambers having an inlet opening, and an outlet or discharge opening, and closures by which said openings may be independently opened or closed, whereby in addition to said local circulation there will be a progressive displacement of air from the open inlet through the connected chambers to the open outlet.

2. A drying apparatus comprising a plurality of heating chambers each having an inlet and an outlet with closures for the inlets and outlets which may be independently opened or closed and by means of which the inlet of any heating chamber and the discharge from an adjacent heating chamber may be opened, a drying chamber for each heating chamber, and means to establish a local circulation of air through each drying chamber and its corresponding heating chamber and also to produce a progressive displacement of air from the open inlet through the drying chambers and heating chambers in succession to the open outlet.

In testimony whereof, I have signed my name to this specification.

HERMANN HAAS.
